UNITED STATES PATENT OFFICE.

WEBB JAY, OF CHICAGO, ILLINOIS.

FUEL-SUPPLY INDICATOR FOR AUTOMOBILES.

Application filed April 11, 1916. Serial No. 90,327.

To all whom it may concern:

Be it known that I, WEBB JAY, a citizen of the United States, residing at Chicago, in the county of Cook and State of Illinois, 5 have invented certain new and useful Improvements in Fuel-Supply Indicators for Automobiles, of which the following is a specification.

My invention relates in general to gravity 10 feeding mechanism for automobile engines, and more particularly to means for disclosing to the driver of an automobile the operative condition of the feeding mechanism, the rate of consumption of the fuel, and the 15 completion of the fuel supply.

In fuel feeding apparatus of the character 20 to which my present invention relates, an auxiliary fuel tank is provided at a level above that of the carburetor into which the fuel is intermittently drawn from the main fuel tank to replace fuel supplied from the auxiliary tank through the carburetor to the engine. A partial vacuum is formed in the auxiliary tank usually by intermittently 25 connecting the same with the manifold of the engine, such intermittent connection being controlled by the fuel level in the auxiliary tank. It is desirable that the operative condition of the feeding mechanism 30 should be visible to the driver of the automobile in order that he may know whether the fuel is being properly delivered to the auxiliary tank, and may also be advised as to the quantity of fuel which is being consumed. 35

The primary object of my invention is to provide fuel feeding apparatus of the character referred to in which the driver while in his seat may observe the operation 40 of the fuel feeding apparatus so that he may know whether or not the proper amount of fuel is being supplied to the auxiliary tank and delivered from it to the engine.

A further object of my invention is to provide means for registering the operation of the fuel feeding apparatus in order that the amount of fuel which is being consumed by the engine may be disclosed to the driver. 45

A still further object of my invention 50 is to provide an improved fuel feeding apparatus for automobile engines which will be

convenient in use and efficient in operation.

My invention will be more fully disclosed hereinafter with reference to the accompanying drawings, in which the same is illustrated as embodied in a convenient and practical form, and, in which,—

Fig. 1 is an elevational view of a fuel feeding apparatus embodying my invention, the automobile being indicated in dotted lines;

Fig. 2 is an enlarged view showing in vertical section the auxiliary fuel tank and enclosed parts;

Fig. 3 is a sectional view on line 3—3 of Fig. 4, through the indicating mechanism;

Fig. 4 is a central sectional view on line 4—4 of Fig. 3;

Fig. 5 is an elevational view of the auxiliary tank and indicating and registering mechanism connected therewith;

Fig. 6 is an elevational view of a modified form of indicating and registering device;

Fig. 7 is a detail sectional view of the operating mechanism of the device shown in Fig. 6; and

Fig. 8 is a sectional view on the line 8—8 of Fig. 7.

Similar reference characters are used to designate similar parts in the several figures of the drawings.

Reference letter A indicates an automobile of any suitable construction, the same being shown in dotted lines. The engine cylinders are also indicated in dotted lines at B, as is also the carburetor C, which may be of any suitable construction for supplying the explosive mixture to the intake of the engine cylinders.

D indicates a storage tank for containing a supply of gasoline or other liquid fuel, 90 which is located at a level below that of the carburetor, as is the case with most modern automobiles. F designates an auxiliary fuel tank which is suitably supported at a level above the carburetor and preferably 95 within the hood of the automobile adjacent the dashboard. A conduit E extends from the main fuel tank D to the interior of a float-chamber F¹, supported within the auxiliary tank F. G designates a conduit communicating with the float-chamber and leading to the engine manifold. H designates a

conduit leading from the bottom of the auxiliary tank F to the carburetor C. F² indicates a float located within the chamber F¹, and operatively connected to a suitable valve 5 mechanism for intermittently controlling the communication between the float-chamber and the conduit G, and coincidently controlling the communication between the float-chamber and the atmosphere. When 10 the delivery of the fuel from the float-chamber F¹ permits the float to fall a predetermined distance the valve mechanism is operated to close the valve e² controlling the atmospheric connection, and to open the 15 valve e¹ controlling the communication with the manifold. The suction of the engine then produces a partial vacuum in the float-chamber, so that fuel is delivered thereinto from the main fuel tank D until the float has 20 been lifted a predetermined distance, when the valve mechanism is operated to close the valve e¹ and open the air inlet valve e².

The mechanism above described does not in itself constitute my present invention, as 25 the same is covered by patents heretofore granted to me. It is, however, herein illustrated and briefly described in order that my present improvement may be fully disclosed.

30 K designates a conduit leading from the interior of the float-chamber F¹ to a gauge for indicating the pressure within the float-chamber, such gauge is shown as comprising a Bourdon tube k located within a suitable 35 casing L and connected at one end through the coupling K¹ with the adjacent end of the conduit K leading into the auxiliary tank. The opposite end of the tube k is pivotally connected by a link k¹ with a crank-arm k² fixed to a rock-shaft K², one 40 end of which projects in front of the casing L and has fixed to it a pointer M. Adjacent the end of the pointer M is located a dial having thereon suitable graduations m.

45 Carried by the rock-shaft K² is a contact n which is movable relatively to a fixed contact N, which is electrically connected with the winding of a solenoid N' and with a 50 source of electricity, such as a storage battery N². n¹ indicates the plunger of the solenoid which is flexibly connected by a link n² with a crank-arm n³ fixed upon a shaft n⁴ supported within the casing L. Adjacent the crank-arm n³ are pins o¹ and o² located on opposite sides of the crank-arm 55 n³, to limit its movement. The shaft n⁴ is connected to any suitable registering discs O, so arranged and connected that they will be operated each time the plunger is reciprocated by the solenoid.

60 The embodiment of my invention above described operates as follows:

When the float-chamber is connected with the engine manifold the partial vacuum produced in the float-chamber will, through the

connecting conduit K, cause the tube k to contract, thereby moving the pointer M relatively to the adjacent dial. The contraction of the tube k also moves the contact n into engagement with the contact N, thereby closing the circuit to the solenoid N', and causing the plunger n¹ to be reciprocated. The reciprocation of the plunger oscillates the shaft n⁴ through the medium of the crank-arm n³. The registering mechanism 75 is thereby actuated so as to add one unit to the previous record, in a well-known manner. Immediately upon the closing of the valve e¹ and the opening of the air inlet valve e², the partial vacuum is destroyed, 80 so that the tube k expands and returns the pointer M to its normal position relatively to the dial. In this manner each operation of the mechanism in the float-chamber is indicated, and also registered. The indicator 85 by its movement relatively to the dial discloses to the driver the degree of vacuum produced in the float-chamber, and consequently discloses to him whether or not the fuel is being drawn in proper quantity from 90 the main fuel tank into the auxiliary tank. Should there be an obstruction in the fuel conduit leading to the float-chamber, a greater degree of vacuum will be indicated. On the other hand, should the fuel in the 95 main tank be depleted, air will be drawn into the float-chamber, thereby destroying the vacuum and disclosing to the driver, through the position of the pointer of the vacuum gauge, the fact that a new supply 100 of fuel must be obtained before the limited supply in the auxiliary tank is exhausted.

Inasmuch as the capacity of the float-chamber is known, and the amount of fuel which is discharged therefrom between the 105 successive operations of the valve mechanism by the float, the pointer M indicates to the driver the amount of fuel which is being consumed. The register enables the driver to know the amount of fuel which 110 has been consumed in a given time, or in running a given distance.

In Figs. 6, 7, and 8, I have illustrated a modified mechanism for actuating the register through mechanical connection with the 115 vacuum gauge, in lieu of the electrical operating means shown in Figs. 3 and 4. Reference character M² indicates a sleeve mounted upon the shaft K². Fixed to one end of the sleeve M² is a pointer M¹ which 120 overlies a dial m¹ in the front casing L. The opposite end of the sleeve M² has fixed thereto a ratchet wheel P, the teeth of which are successively engaged by a pawl P¹ pivoted to a crank-arm p¹ fixed to the shaft K². The 125 end of the pawl P¹ is recessed, as shown in Fig. 8, such recess cooperating with a fixed pin p² to permit the engagement of the pawl with the ratchet wheel only during a limited movement of the pawl with the crank-arm 130

*p*¹. *Q* designates a spring-pressed pawl for retaining the ratchet wheel in the positions into which it is moved step by step by the actuating pawl *P*¹.

5 The form of my invention shown in Figs. 6, 7, and 8, operates as follows: The shaft *K*² is oscillated each time the tube *k* contracts, and the oscillation of the shaft causes the pawl *P*¹ to be moved relatively to the 10 ratchet wheel *P*. The pin *p*² effects the lifting of the pawl during the movement of the shaft *K*² towards the right in Fig. 8, that is during the contraction of the tube *k*. When the valve mechanism in the auxiliary 15 tank is actuated to disconnect communication with the exhaust and to open communication with the atmosphere, the tube *k* expands which oscillates the shaft *K*² in a reverse direction, and with it moves the pawl *P*¹ towards the left, as shown in Fig. 8. When the pawl *P*¹ has moved to such a position that the recess in the end thereof registers with the pin *p*², the pawl engages a 20 tooth on the ratchet wheel *P* and moves the ratchet wheel a distance of one tooth during the final oscillation of the shaft *K*². The movement of the ratchet wheel *P* is communicated through the sleeve *M*² to the pointer *M*¹, so that the latter is moved relatively to the dial *m*¹ a distance to indicate 25 one operation of the valve mechanism in the auxiliary reservoir. The amount of fuel delivered to the engine is consequently registered, inasmuch as the volume which is supplied thereto at each operation of the valve mechanism is known. The quantity of fuel consumed by the automobile during a given time, or in driving a given distance, is consequently registered.

30 40 From the foregoing description it will be observed that by my invention the driver of an automobile is enabled to observe the operation of the fuel feeding apparatus and to thereby know whether a proper quantity of fuel is being consumed, and also the operative condition of the apparatus, and is advised when the main fuel tank is empty. It will furthermore be seen that by my invention a record is kept of the amount of fuel 45 consumed by the engine.

50 What I claim is:

1. In a fuel feeding apparatus for engines, the combination with a receptacle having a fuel delivery outlet therefrom and 55 communicating with the atmosphere, of conduits connecting said receptacle with a liquid fuel supply and with an air exhausting means, automatic means actuated by the amount of fuel in said receptacle controlling 60 the connection between said receptacle and the exhausting means, and an indicator connected with said receptacle and operated by the pressure therein to disclose the operation of said automatic means.

65 2. In a fuel feeding apparatus for engines,

the combination with a receptacle having a fuel delivery outlet therefrom, of conduits connecting said receptacle with a liquid fuel supply and with an air exhausting means, means for intermittently controlling the connection of said receptacle with the exhausting means, and means for registering the successive operations of said automatic means.

70 3. In a fuel feeding apparatus for engines, the combination with a fuel-containing receptacle having a delivery outlet, of exhausting mechanism connected with said receptacle, automatic means for placing said receptacle in communication with said exhausting mechanism upon the discharge of a predetermined amount of fuel from said receptacle, and means actuated by the pressure in said receptacle for indicating each 75 operation of said automatic means.

80 4. In a fuel feeding apparatus for engines, the combination with a fuel-containing receptacle having a delivery opening therefrom, of intermittently operating automatic means for supplying predetermined quantities of fuel to said receptacle, and mechanical means automatically operated simultaneously with the operation of said automatic means for indicating each operation of said 85 means.

90 5. In a fuel feeding apparatus for engines, the combination with a fuel-containing receptacle having a delivery outlet therefrom, of intermittently operating automatic means for exhausting air from said receptacle, a fuel tank connected with said receptacle, and an indicator automatically operated simultaneously with the operation of said means to disclose the successive operations of said 95 automatic means.

100 6. In a fuel feeding apparatus for engines, the combination with a fuel-containing receptacle having a delivery outlet therefrom, of intermittently operating automatic means for exhausting air from said receptacle, a fuel tank connected with said receptacle, and a pressure gauge communicating with said receptacle to indicate the successive operations of said automatic means.

110 7. In a fuel feeding apparatus for engines, the combination with a fuel-containing receptacle having a delivery outlet therefrom, of a fuel tank, a conduit leading from said fuel tank to said receptacle, an exhausting mechanism, intermittently operating automatic means for connecting said exhausting mechanism with said receptacle, and means for registering the successive operations of said means.

115 8. The combination with a liquid fuel supply system, including an auxiliary supply receptacle, and suction means for automatically periodically refilling said receptacle, of a register and means connected with said receptacle responsive to the change of pres- 120 125 130

4
sure therein for actuating the register to indicate the quantity of liquid supplied.

9. The combination with a liquid fuel supply system, including an auxiliary supply tank, and suction means for periodically automatically refilling said tank, of a suction operated motor actuated upon each refilling

of the tank, and a register operated by said motor for indicating the quantity of liquid used.

In testimony whereof, I have subscribed my name.

WEBB JAY.
